UNITED STATES PATENT OFFICE.

JOHN W. TOWLER, OF CINCINNATI, OHIO.

COMPOSITION SHINGLE.

Application filed August 8, 1924. Serial No. 730,862.

To all whom it may concern:

Be it known that I, JOHN W. TOWLER, a citizen of the United States, residing at Cincinnati, in the county of Hamilton and State of Ohio, have invented new and useful Improvements in Composition Shingles, of which the following is a specification.

My invention relates to an improvement 10 in composition shingles and more particularly to such shingles provided with a metal band secured thereto.

One of the objects of this invention is to provide an improved method of securing the 15 free or loose ends of the flexible shingles in place.

Another object is to provide a clamp to insure proper spacing so that no coarse lines need be drawn, reducing the cost of laying.

20 Another object is to provide a clamp which accurately acts as a guide so that a person of comparatively little skill can lay them symmetrically, resulting in uniformity in roof coverage and the area exposed on 25 each shingle.

My invention is illustrated in the accompanying drawings, in which—

Figure 1 is a top plan view of a roof section constructed with my improved shingles, hidden clamps and turned under corners being dotted in,

Fig. 2 is a plan view of the face of one of my shingles,

Fig. 3 is a plan view of the reverse side 35 of the same shingle, and

Fig. 4 is an enlarged section on the line 4-4 of Fig. 2.

Referring now to the drawings, A is a composition shingle, adapted to be laid in 40 diamond position with the bent-under end a down.

At a suitable distance from the opposite upper corner a band B preferably made of metal adapted to withstand corrosion, extends across the face of the shingle, on a line parallel with the edge a¹ of the lower end. This band is bent over the edges of the shingle, its ends b¹ are bent over upon the under side of the shingle and may be 50 held by wire brads, tongues b¹, b² or in any convenient manner. If the shingles are carefully handled simply notching the ends of the shingle to form recesses to receive the band at the places where its ends are bent over the shingle edges, is sufficient.

Midway of its length on the face of the

shingle the band B¹ is bent outwardly at b² just high enough to allow a shingle corner to pass under it, that is just the thickness of a shingle. The upright edges b³ next this bent portion are preferably substantially at right angles to the main faces of the band and these perpendicular edges b³ are preferably substantially parallel with the two edges of the shingle that form the adjacent corner.

With shingles made as described the manner of laying is as follows: Referring to Fig. 1, shingle A¹ is placed in position and nailed at c¹, c², then shingle A² is placed with

the right edge of its bent-under end a resting against the contiguous portion of the lower left edge of shingle A¹, and the lower left edge of A¹ in line with the left edge of the bent-under end of A², and the lower

right edge of A² resting against the left perpendicular edge b³ of the band B of the shingle A¹, and nailed at c³ and c⁴. The shingle A³ is then placed in position with its lower left edge against the right edge b³ of the band B of the shingle A² and the left edge of its bent-under point resting against the lower right edge of A¹ for the full width of said bent-under corner and nailed at c⁵ and c⁶. The shingle A⁴ is then 50 laid, first hooking its lower bent-under corner under the raised portion b² of the band B of shingle A¹ and resting its lower left edge against the edge b³ of the band B of the shingle A² and its lower right edge 55 against the edge b³ of the band B of the shingle A³ and nailed at c⁷ and c⁸, etc.

I claim as my invention and desire to secure by Letters Patent of the United States:

1. A composition shingle having in combination a bent-under corner and a band secured to the shingle and across the face of said shingle near the opposite diagonal corner, said band having a part thereof midway its length raised above the surface of said shingle and parallel with its face and so shaped as to receive the bent-under corner of the similar overlapping shingle placed directly above the first, and to form a guide for the contiguous edge of each of the overlapping superimposed lateral shingles.

2. A composition shingle having in combination a bent-under corner and a metal band across the face of said shingle and secured to said shingle near the opposite diagonal corner, said band bent upwardly midway of said shingle face to form an elongated

eve into which the bent under corner of the similar overlapping shingle placed directly above the first may be hooked, the shoulders formed on the band by such bending forming a guide for the contiguous edge of each of the adjacent overlapping superimposed lateral shingles.

3. The combination with an asphalt shingle, of a fastener and guide, comprising a strip of sheet metal formed with a central pressed up portion, and spurs extending

from said strip for permanently securing the strip to said shingle, said fastener and guide being spaced from one corner of said shingle, said pressed up portion being formed with inclined sides acting as guides for guiding or causing adjacent shingles to be correctly positioned in respect to the first mentioned shingle.

In testimony whereof, I have hereunto set my hand.

JOHN W. TOWLER.
